UNITED STATES PATENT OFFICE.

ARTHUR J. MUNDY, OF BOSTON, MASSACHUSETTS, ASSIGNOR TO THE GRAY
TELEPHONE COMPANY OF WATERVILLE, MAINE, OF SAME PLACE.

METHOD OF SIGNALING.

SPECIFICATION forming part of Letters Patent No. 667,136, dated January 29, 1901.

Application filed May 25, 1900. Serial No. 18,016. (No model.)

To all whom it may concern:

Be it known that I, ARTHUR J. MUNDY, a citizen of the United States, residing at Boston, in the county of Suffolk and State of Massachusetts, have invented a new and useful Improvement in Methods of Signaling, of which the following is a full, clear, and exact description, reference being had to the accompanying drawing, forming a part of the specification, in explaining its nature.

The invention relates to the method of signaling herein described. The method is applicable for use in any medium. I shall describe it, however, as applicable to submarine signaling. Where so applied, it is practiced by submerging three fixed signaling-points at known distances from each other in a triangular relation to each other and actuating them in any convenient or desirable way, but preferably from a single actuating-station more or less remote from the signals. Any suitable signals may be used, and I will mention among them the apparatus described in the patent to Elisha Gray and myself, No. 636,519, dated November 7, 1899. I would be understood, however, as not confining myself to any particular signals or means of actuating them. The signals may be sounded simultaneously or they may be sounded successively, and they may be differentiated from each other in any desired way—that is, one signal may be indicated by a single sound impulse, the second by two sound impulses, and the third by three sound impulses, or the first may have a tone of a certain pitch, the second a tone of another pitch, and the third a tone of a third pitch. It is desirable when three signal-stations triangularly arranged are used in practicing the method that the distance between the signaling devices be known and that the difference in time of their operation where they are operated successively be also known. With these determinate factors and with the knowledge of the number of feet per second sound travels it is then possible for an observer within the area in which said sounds are audible to locate his exact position in respect of the fixed signaling-points, for it then becomes a matter of computation based upon the distances between the signals, the rate at which the

sounds travel, and the intervals between the times when the sounds reach the observer. Sound travels in water at the rate of four thousand seven hundred and twelve feet per second and in the air at the rate of eleven hundred feet per second. The sounds from each signal radiate in all directions and travel with equal speed, and this fact enables the method to be carried into effect and applied by means of the chart represented in the drawing, which forms a part of the specification.

Referring to the drawing, A represents one signal-point, B the second signal-point, and C the third signal-point. They are represented as disposed with respect to each other to form the points or apexes of an equilateral triangle and are assumed to be separated from each other by a distance of four miles. If the observer were to be located in the center of the triangle and the three signals A, B, and C were to be simultaneously actuated, he would hear the three signals at exactly the same instant. If now the position of the observer were shifted so as to move along a line drawn between the center of the triangle and one of the signaling-points and the three signals were again sounded simultaneously, the observer would hear the nearest signal before he heard the two others, which would then immediately sound simultaneously, the latter still being equally distant from the new position of observation. If the observer again change his position by moving either to the right or to the left of the said line, so that all three signals are at different distances from him, and again the three signals are sounded simultaneously, he will then hear them successively at intervals which bear a direct relation to the distances separating him from each of them. If the signals are sounded in successive order, then the time between the intervals of their sounding becomes an element for consideration, and the drawing represents a chart or diagram for an arrangement in which the signals are sounded successively at regular intervals of ten seconds between each, the three signals sounding in a cycle of thirty seconds. The time at which the signals thus sounded will reach certain predetermined distances from the signal are indicated upon the chart by the straight lines

a, b, and c, which intersect at the exact center of the triangle, and the curved lines d. These curved lines intersect each other and the straight lines and the intersecting points thus created provide predetermined positions having definite distances from and angles with respect to the three signal-stations, and by means of the sounds received from the signals the observer is enabled to ascertain upon the chart his exact position with regard to the signaling-stations, each of the lines having at its end or otherwise located upon it a number which indicates its value in making this determination. For instance, suppose the observer should ascertain that the interval of time between the first and second signals A and B that he should hear should be eight and one-half seconds, the interval of time between the second and third signals B and C should be ten and one-half seconds, and the interval of time between the third and first signal again sounded (C and A) should be eleven seconds. He would then with his chart find the intersecting-point of the lines numbered "8½," "10½," and "11," and following them to their point of intersection, as indicated by a circle on the diagram, he would discover his relation both as to distances and as to angles of direction to the three signaling-points.

When the three signals are actuated successively at intervals of ten seconds, the sum of the intervals thus taken by the observer should always be thirty—that is, upon the supposed position that he accurately notes the time between the soundings of the signals as they reach him. When only two of the signals are audible, they will guide the observer to the nearest point, where the third signal can be also heard.

I do not confine the invention to a method employing three signals, as in some instances two may be used or even more than three.

I have described and claimed in a separate application the chart or means for carrying the method into effect.

Having thus fully described my invention, I claim and desire to secure by Letters Patent of the United States—

1. The method herein described consisting in disposing a number of sound-producing devices of differing identities in known position and sounding said devices either simultaneously or successively at known intervals of time thereby affording means whereby an observer may estimate from said signals so sounded his relative position to the signals.

2. The method of submarine signaling consisting in disposing a number of sound-producing devices of differing identities in known positions and sounding the said submerged devices either simultaneously or successively at known intervals of time and whereby the sound impulses are either simultaneously or successively received and transmitted by the water in which they are submerged thereby affording means whereby an observer may estimate from said signals so sounded his relative position to the signals.

3. The method herein described consisting in disposing three sound-producing devices of differing identities in triangular relation to each other, and sounding said devices either simultaneously or successively at known intervals of time thereby affording means whereby an observer may estimate from said signals so sounded his relative position to the signals and the angles which he may occupy in relation to them.

4. The method of submarine signaling consisting in disposing three sound-producing devices of differing identities in a triangular relation to each other and sounding said submerged devices either simultaneously or successively at known intervals of time whereby the sound impulses are either simultaneously or successively received and transmitted by the water in which they are submerged thereby affording means by which an observer may estimate from said signals so arranged and sounded his relative position to the signals and the angles which he may occupy in relation to them.

ARTHUR J. MUNDY.
